UNITED STATES PATENT OFFICE.

EMIL TYDEN, OF HASTINGS, MICHIGAN.

PEDESTAL-EXTENSION-TABLE LOCK.

981,144.

Specification of Letters Patent. Patented Jan. 10, 1911.

Application filed March 8, 1909. Serial No. 482,163.

To all whom it may concern:

Be it known that I, EMIL TYDEN, a citizen of the United States, residing at Hastings, in the county of Barry and State of Michigan, have invented new and useful Improvements in Pedestal-Extension-Table Locks, of which the following is a specification, reference being had to the accompanying drawings, forming a part thereof.

10 The purpose of this invention is to provide an improved device for locking together the divided members of the pedestal of an extension table.

15 It consists of the features of construction shown and described as indicated in the claims.

20 In the drawings:—Figure 1 is a vertical longitudinal section of a pedestal table equipped with this invention. Fig. 2 is a detail section at the line 2—2 on Fig. 1. Fig. 3 is a top plan view, partly sectional, at the same plane as Fig. 2. Fig. 4 is a detail section at the line 4—4 on Fig. 2. Fig. 5 is an enlarged detail section of the latch-25 engaging device at the same plane as Fig. 1. Fig. 6 is a section at the line 6—6 on Fig. 5. Fig. 7 is a view similar to Fig. 5 showing a modified form of the latch-engaging device. Fig. 8 is a detail section on the line 8—8 of Fig. 1, showing in side elevation, a locking segment.

30 Upon the two members of the pedestal there are mounted respectively coöperating engaging devices, 1 and 2, one of said devices,—the element, 1,—being pivotally mounted. Upon the pedestal having the pivotally mounted device there is mounted a vertical rock shaft, 3, having at the lower end a laterally jutting pivot stud and operating lever arm, 4, on which the engaging device, 1, is pivoted. Said pivot stud or lever arm, 4, protrudes into a horizontally extended slot, 5^a, in the bracket, 5, in which the vertical rock shaft is stopped and journaled for turning about its vertical axis. This bracket is most conveniently made of sheet metal folded to form a yoke or loop between whose side members the vertical rock shaft, 3, extends, one of said side members having the slot, 5^a, mentioned into which the stud, 4, protrudes, the cross neck, 5^b, of the bracket having an aperture, 5^c, through which the pivoted element protrudes. Said pivoted element, 1, has a stop lug or tail piece, 1^a, projecting from its upper edge in position for encounter with the cross neck of

the bracket when the pivot stud or lever arm, 4, of the rock shaft, 3, is approaching the inner end of the slot, 5^a, so that the remote hooked end of the element, 1, will be lifted 60 out of engagement with the element, 2, by the time the lever arm, 4, reaches the inner end of said slot and will be dropped into position for engagement with said element 2 during the first part of the movement of 65 said stud in the opposite direction. At the upper part of the rock shaft, 3, it may be provided with any suitable means for rocking it through an angle of about sixty degrees for causing the pivot stud or lever arm, 4, to traverse the length of the slot, 5^a, and any suitable means may be provided for 70 rocking the rock shaft by means of such operating device. As illustrated, the rock shaft is provided at its upper end with a 75 short crank arm, 3^a, which swings over a segment, 6, mounted on the top of the pedestal provided with a shoulder, 6^a, having one side sloping, and the other side abrupt, the lever arm snapping into engagement with the 80 abrupt shoulder at the point in the rocking of the shaft at which the short lever arm, 4, is at the outer limit of the slot, 5^a.

75 The operation of the device will be obvious upon inspection as follows: The lever arm, 3^a, being swung to the opposite limit of its movement from that at which it may be engaged with the abrupt shoulder of the segment, 6, the engaging device, 1, is projected toward the opposite pedestal member, 90 and upon the members being closed together passes into position for engagement with the engaging device, 2, on said opposite member. The operator then rocking the shaft, 3, by means of the lever arm, 3^a, first causes the 95 element, 1, to drop into engagement with the element, 2, and then to draw said element, 1, back toward the pedestal member on which it is mounted, drawing the two pedestal members into close engagement, 100 and the crank arm being at the limit of that movement engaged with the abrupt end of the shoulder, 6^a, the two pedestal members are locked together. It will be understood 105 that the device in the form described and without means for operating the rock shaft except such as may be accessible directly at the top of the pedestal is intended to be applied upon tables having the top members separable for some distance more or less 110 before the pedestal members are separated, so that access is thereby obtained to the up-

per end of the rock shaft, and for locking the pedestal, the operator having first separated the table members as indicated, getting access to the crank arm, 3^a, releasing it from the segment and rocking it back in the opposite direction, will cause the element, 1, to be thrust inward by the pivot stud, 4, and such inward thrust will first relax the clamping engagement of the two members, 1 and 2, and next by the encounter of the tail 1^a of the element 1, with the cross neck of the bracket 5, lift the member, 1, out of engagement with the member, 2, so that the pedestal members may be separated.

15 Applying any locking device of the general class to which the above described device belongs,—that is, having two engaging elements secured to the pedestal members respectively and adapted to become engaged as they approach, one of them being operable to draw the two members together after they are engaged,—it is a matter of great convenience to be able to adapt the same devices to pedestals of slightly different width or distance between the opposite walls to which their respective engaging devices are connected; and for that purpose the element, 2, is desirably of the form shown in the drawings, in which it consists of a lever pivoted between its ends upon a fixed bracket, 9, on the pedestal member, the element, 1, being engaged with the upper end of said lever, the lower end being provided with means for adjusting it in and out with respect to the pedestal wall on which the device is mounted. A convenient means for such adjustment consists in a threaded post, stud or bolt, 10, rigid with the bracket, 9, extending through the lower end of the element, 2, and across a nut aperture therein in which is lodged a nut, 11, engaged with the threaded bolt or stud, 10, the nut being fitted tightly to the bolt so as not to be liable to movement thereon without action of the operator, serves to hold the element, 2, in position to which it may be adjusted by screwing the nut one way or the other of the bolt, thereby varying the distance from the pedestal of the upper end with which the element, 1, is engaged. The range of adjustment which may be thus provided can be made sufficient for considerable variation in the size of the pedestal. In order that the engagement of the hooked end of the element, 1, with the upper end of the element, 2, may at all times be secure, notwithstanding the oblique position to which the element, 2, may be adjusted in the manner above described, the said element, 2, has the upper end portion with which the hook is engaged consisting of a mere cross bar, 2^a, and the element, 1, has its hook nose adapted to engage partly around said cross bar so that the angle or inclination of the element, 2, as a whole has no effect upon the engage-

ment. A convenient form for this element, 2, accomplishing all the purposes above described is that illustrated in which it is made by folding a piece of sheet metal or plate into channel form, the bracket, 9, being 70 made of an angle plate, as seen in Fig. 3, one flange of the angle plate being entered between the channel sides of the element, 2, for pivotal connection therewith, the web of the channel being cut away at 2^a below the 75 portion left standing to form the cross bar, 2^a, the channel sides being apertured at 2^b for the nut, 11, and the webbing apertured at 2^c for the bolt, 10.

10 A modification of means for adjusting the 80 element, 2, is shown in Fig. 7, consisting in substituting for the stud, 10, and nut, 11, a rib or flange, 9^b, jutting from the bracket, 9, between the channel sides of the element, 2, at the lower end, the channel web being cut 85 away entirely below the pivot, slots, 2^d, being made in the channel sides and a slot, 9^c, in the flange, 9^b, said slots of the channel walls and said lug crossing each other so that a clamping bolt, 12, may extend through 90 them for clamping the channel sides on to the lug at adjusted position of the parts.

I claim:—

1. In a pedestal extension table, in combination with the divided pedestal members, 95 coöperating engaging devices on the pedestal members respectively; a vertical rock shaft mounted on one pedestal member having a laterally projecting lever arm on which one of said engaging elements is pivoted for vertical swinging and loosely for permitting rotation of the rock shaft through a limited angle; means for guiding said pivoted element longitudinally toward and from the opposite pedestal member and in its said vertical pivotal movement, said element having above its pivot an inwardly facing shoulder; a stop fixed with respect to the axis of the rock shaft for encounter with such shoulder at the inward limit of the 105 range of movement of the pivot stud, and means for turning the rock shaft and for locking it at the inner limit of such movement.

2. In a pedestal extension table, in combination with the divided pedestal members, 115 coöperating engaging elements on the members respectively, one of said elements being pivotally mounted on the member to which it pertains; a vertical rock shaft journaled 120 on said member and provided with a laterally jutting lever arm which serves as the pivot for such pivotal engaging element; a bracket mounted adjacent to the rock shaft and fixed with respect to the pivotal axis 125 of the latter, having a slot extending in the plane of the movement of said lever arm pivot with which the latter is engaged, the pivoted element having an inwardly facing shoulder; means on the bracket in position 130

for encounter by said shoulder at the limit of the inward movement of said pivoted element, and means for rocking the shaft and for locking it at one limit of its rocking movement.

5 3. In a pedestal extension table, in combination with two divided pedestal members, coöperating engaging devices mounted on the two members respectively for connecting them together; means for operating upon one of said engaging devices for forcing the pedestal members together after they are connected, the other engaging device being pivotally mounted on the pedestal member 10 to which it pertains and positioned for engagement with the coöperating element at a distance from its pivot, and means for adjusting it about its pivot to vary the distance of the point of engagement from the 15 parting plane.

20 4. In a pedestal extension table, in combination with the divided pedestal members; coöperating engaging devices mounted on the two members respectively; means for operating upon one of said elements to force the two pedestal members together after said elements are engaged, the other element being lever fulcrumed intermediate its ends upon the pedestal member on which it is 25 mounted and positioned for engagement at one end with the coöperating element, and means for adjusting it at the other end toward and from the parting plane.

25 5. In a pedestal extension table, in combination with two divided pedestal members; coöperating engaging devices mounted on the members respectively for connecting them, one of said elements being a lever fulcrumed between its ends on the pedestal 30 member to which it pertains, positioned for engagement of one end with the coöperating

element, and provided at the other end with means for adjustably securing that end at varying distances from the parting plane.

6. In a pedestal extension table, in combination with divided pedestal members, co-operating engaging devices on the pedestal members respectively; a vertical rock shaft mounted on one pedestal member having a projecting lever arm loosely engaging one 45 of said engaging elements; means for guiding said element longitudinally toward and from the opposite pedestal member; an abutment fixed with respect to the axis of the rock shaft, said element having a coöperating 50 abutment for encounter with the first at the inward limit of its longitudinal movement, and means for operating and locking the rock shaft.

7. In a pedestal extension table, in combination with two divided pedestal members, coöperating engaging devices mounted on the members respectively for connecting them, means for actuating one of said members to draw the pedestal members together, 60 the other of said members being mounted intermediate its ends on the pedestal member to which it pertains, having one end provided with means for engaging the other member, and a screw and nut connecting its 65 other end with said pedestal member for adjustably securing said end at all varying distances from the parting plane within the range of adjustment of said nut and screw.

In testimony whereof, I have hereunto set 75 my hand at Chicago, Illinois, this 3d day of March, 1909.

EMIL TYDEN.
